HINGE

Filed Sept. 29, 1927

INVENTOR
Harry E. Sipe

E. Thompson
ATTORNEY

UNITED STATES PATENT OFFICE

HARRY E. SIPE, OF NEW YORK, N. Y.

HINGE

Application filed September 29, 1927. Serial No. 222,694.

This invention relates to hinges and particularly to devices of this class of the covered joint type; and the object of the invention is to provide a hinge, the separate butts of which are composed of sheet metal and provided with interengaging knuckles coupled together by a pivot pin, and the provision of a casing or jacket encircling or partially encircling the outer face portions of the knuckles of the hinge to form a finishing strip or covering which conceals and protects the knuckles of the hinge exposed through the door and door frame; a further object being to provide a finishing strip and covering of the class described composed of yieldable material whereby the same is free to flex in the movement of the hinge in the operation of opening and closing a door; a further object being to provide a yielding strip of the class specified having resilient properties to act as a resilient stop or door check, compensating for shocks to which the hinge and door may be subjected in the forceful movement of the door into a fully open position; a further object being to provide means on the hinge butts, door and door frame for retaining the finishing strip or hood portion in connection therewith and preventing the accidental displacement therefrom, as well as to permit of relative movement of the strip with reference to either the door or door frame; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view of a hinge made according to my invention.

Fig. 2 is a section on the line 2-2 of Fig. 1.

Fig. 3 is a view, similar to Fig. 2 but showing the parts in a different position.

Fig. 4 is a view similar to Fig. 2 but showing a modification; and,

Fig. 5 is a view similar to Fig. 4 but showing the parts in a different position.

In Figs. 1 to 3 inclusive, I have shown at 10 a part of a door frame, and at 11 a part of a door mounted in said frame. In the construction shown, the door and door frame includes sheet metal portions 10^a and 11^a which constitute facings therefor. The door frame 10 is recessed as shown at 12 to receive one butt 13 of a hinge, and the door is recessed as seen at 14 to receive the other hinge butt 15.

In the construction shown, both hinge butts 13 and 15 are fashioned from sheet metal folded centrally to form circular pintle bearings 13^a and 15^a which are arranged in alternate relation when the separate butts are coupled together by a pintle pin 16 passed through the bearings 13^a and 15^a, and the shanks 13^b and 15^b of the butts are composed of two thicknesses of the sheet metal from which the same are formed. However, my invention is not necessarily limited to the specific manner of constructing the butts nor to the particular shape or contour thereof herein shown and described.

As seen in Figs. 2 and 3 of the drawing, the knuckle or bearing portions of the butts are contained within the outer faces of the door and door frame when viewed externally thereof and the adjacent portions of the door and door frame are recessed as seen at 17 and 18 to provide a clearance around the knuckles or bearing 13^a and 15^a.

Mounted on the outer face of the pintle bearings of the butts is a finishing, covering and cushioning strip 19, arc-shaped or semi-circular in cross sectional form, the inside diameter of said strip being such as to fit snugly upon the bearings 13^a and 15^a while the outer diameter is such as to fit and operate snugly in the recesses 17 and 18. The end of the strip operating in the recess 18 may be enlarged to a slight degree as seen at 20 to fit in a corresponding enlargement in the recess 18 to prevent movement of said end of the strip, whereas the other end of the strip is preferably provided with a metallic, fibrous or other facing 21 which permits of the free movement of said strip into and out

of the recess 17 in the operation of opening and closing the door.

The strip 19 may be composed of any desired material and is preferably composed of a yielding, flexible and resilient material, such for example as rubber or composition rubber. This strip will extend the full length of the respective hinge butts, said butts being of the elongated type in the construction shown and will form a neat and finished attractive covering, casing or jacket for the pintle bearing portions of said butt, and a finishing strip externally of the door and door frame. The strip may be produced in a color or coated with a color similar to, in harmony with or contrasting to the coloring employed on the door and door frame.

In Figs. 4 and 5 of the drawing, I have shown a slight modification of the construction shown in Figs. 1 to 3 inclusive, wherein 22 represents the door frame, 23 the door, 24 the hinge butt secured to the door frame, and 25 the hinge butt secured to the door. These butts are coupled together by pintle pins 26 passed through the pintle bearings or knuckles of the respective butts, which in the construction shown, are circular in form and fashioned from a single sheet or piece of metal. In this construction, I employ in conjunction with the butts 24 and 25, supplemental butt parts 24^a and 25^a, the outer ends of which terminate in arc-shaped segments 24^b and 25^b, which partially encircle the pintle bearings of the respective butts and are arranged in spaced relation thereto to form recesses 27 and 28 therebetween. Mounted on the pintle bearings of the hinge butts and operating in the recesses 27 and 28 is a strip 29 similar to the strip 19, which forms an attractive covering or jacket for enclosing the pintle bearings of said hinge butts. This strip may be constructed of the same material as the strip 19. It will also be seen that in the construction shown in Figs. 4 and 5, the pintle bearings of the butts are arranged outwardly of the outer faces of the door and door frame, but this arrangement is not essential.

In both forms of construction shown, it will be understood that the strips 19 and 29 may be inserted in position after the hinge has been assembled in the door frame by placing the ends of said strip in the respective recesses provided therefor. In the event of destruction or wear on said strip requiring the replacement thereof, the same may be forcibly removed, and a new strip substituted. In addition to operating as an attractive covering and finishing strip which encloses the joint of the hinge and forms a neat and finished outer appearance, the strip operates, in the act of opening the door and forcibly moving the same into a fully opened position, as a resilient shock absorbing and stopping or checking body, it being understood

that as the door is swung open, the end 21 of the strip moves into the recess 17 until it engages the inner wall 17^a of said recess, after which the rubber is pressed to the degree governed by the force or pressure applied to the door. As previously stated, the strips 19 and 29 fit snugly in their respective recesses to form a seal and closure between the strip and its adjacent butt parts to prevent water and other substances from entering said recesses.

My improved hinge construction may be used in hanging doors of any kind or class but is particularly designed for use in connection with the door and door frames of motor vehicles. While I have shown hinge butts of certain form and contour, it will be understood that my invention is not necessarily limited in this respect, and various other changes in and modifications of the construction herein shown and described may be made within the scope of the appended claims, without departing from the spirit of my invention or sacrificing its advantages.

Having fully described my invention, what I claim as new and desire to secure by Letters Patent, is:

1. A hinge of the class described comprising two butt members, interengaging pintle bearings on said butt members, a strip fashioned to partially encircle the pintle bearing of said butts when coupled together to form a body concealing the joint of said butts, said strip being composed of yielding material, means for retaining one side edge of said strip against relative movement with reference to one of said butts and its support, means whereby the other side edge of said strip may be moved relatively to the other of said butts, and means for placing said strip under compression in the operation of moving one butt relatively to the other in one direction.

2. The combination with the pintle bearing portion of a hinge, of a strip of yielding material formed independently of the hinge and extending longitudinally of and partially encircling said pintle bearing portion, means for retaining said strip against displacement from the hinge in the relative movement of the separate butts of the hinge, and said strip having resilient properties to cushion and resiliently check the relative movement of said butts in one direction.

3. The combination with a hinge employing butts having interengaging knuckles, one of said butts being secured to a stationary support, and the other to a swinging member, said support and swinging member having recesses adjacent the knuckles of the respective butts, of a knuckle covering strip mounted on and extending longitudinally of and partially encircling said knuckles and operating in the recesses in said stationary support and swinging member.

4. The combination with a hinge employing butts having interengaging knuckles, one of said butts being secured to a stationary support and the other to a swinging member, said support and swinging member having recesses adjacent the knuckles of the respective butts, of a knuckle covering strip mounted on and extending longitudinally of and partially encircling said knuckles and operating in the recesses in said stationary support and swinging member, said strip having resilient properties, and means whereby the movement of said swinging member in one direction will be resiliently checked by said strip.

5. A hood member for the pintle bearings of hinges of the class described comprising an elongated strip of resilient material, arc-shaped in cross sectional form, means at one side edge of the strip for retaining the same in connection with a support, and the other side edge of said strip having an anti-frictional surface.

6. In a hinge of the class described, the separate butts of which are provided with arc-shaped recesses partially encircling the pintle bearings of said butts, a hood member consisting of an elongated strip arc-shaped in cross sectional form and adapted to be arranged on the pintle bearings only, of the hinge with the side edge portions thereof operating in the recesses of the respective butts, forming an enclosure for the joint of the hinge.

7. In a hinge of the class described, the separate butts of which are provided with arc-shaped recesses partially encircling the pintle bearings of said butts, a hood member consisting of an elongated strip arc-shaped in cross sectional form and adapted to be arranged on the pintle bearings only, of the hinge with the side edge portions thereof operating in the recesses of the respective butts forming an enclosure for the joint of the hinge, and means at one side edge of said strip cooperating with one of said butts for retaining said side portion against displacement from said butt.

8. In a hinge of the class described, the separate butts of which are provided with arc-shaped recesses partially encircling the pintle bearings of said butts, a hood member consisting of an elongated strip arc-shaped in cross sectional form and adapted to be arranged on the pintle bearings only, of the hinge with the side edge portions thereof operating in the recesses of the respective butts forming an enclosure for the joint of the hinge, means at one side edge of said strip cooperating with one of said butts for retaining said side portion against displacement from said butt, and said strip being composed of non-metallic material.

9. In a hinge, the separate butts of which are provided with interengaging knuckles

and a pintle pin for coupling said knuckles to form the joint of the hinge, one of the butts including a member arc-shaped in cross section extending longitudinally of the pintle bearings of the butts and movable with the first named butt, and the other butt being recessed to permit the movement of said arc-shaped member relatively thereto, said member serving to conceal the joint of the hinge in the several positions of the butts.

In testimony that I claim the foregoing as my invention I have signed my name this 23rd day of Sept., 1927.
